UNITED STATES PATENT OFFICE

2,396,808

PRECAST UNIT PAVEMENT, ETC.

Franklin W. Abel, Franklin, Ind.

Application July 28, 1943, Serial No. 496,409

2 Claims. (Cl. 94—13)

This invention relates to a fabricated precast pavement, platform, runway, etc.

The chief object of this invention to produce a structure of the character indicated and from precast concrete so that the several units may be formed, set and cured at one location where most convenient and transported to the place of use if desired and there assembled into structure form.

Another object of this invention is to cast the units without obstructions and thereafter apply thereto connector means by which the same may be handled, which means are of relatively projecting character, and when connected are of drawing type, comparable to turnbuckle usage.

A further object of the invention is to provide a drain type gutter apron whenever and wherever desired.

The chief feature of the invention consists in precasting units and then connecting same together to form a complete pavement, platform or the like, and one wherein leakage through the joints between slabs is prevented to prevent foundation washing or freezing and lifting, etc.

Other objects and features will be set forth more fully hereinafter.

The full nature of the invention will be understood from the accompanying drawings and the following description and claims:

In the drawings

Fig. 1 is a top plan view of a section of a roadway including a plurality of precast slabs connected together and with a curb at one side.

Fig. 2 is an enlarged vertical sectional view thereof taken in the plane of aligned anchoring and connecting means.

Fig. 3 is an enlarged perspective view of a portion of the resilient, expansion and sealing strip including a pocket registering recess.

Fig. 4 is an enlarged perspective view of a cap for closing the pocket.

Fig. 5 is a central section of a modified anchor structure.

Fig. 6 is a plan view of a gutter apron, curb and drain formation.

Fig. 7 is a sectional view taken on line 7—7 of Fig. 6 and in the direction of the arrows.

In Fig. 1 of the drawings 10 indicates precast concrete slabs all of which are identical or same may slightly differ as desired, as regards thickness. These are capable of interconnection to form a complete pavement or roadway with sealing strips 11 between slabs.

Each slab 10 on at least two side faces is provided with upwardly and sidewardly opening

pockets 12 shown most clearly in Fig. 2. Each pocket has a semi-cylindrical bottom surface. Each strip 11 includes a cut out 13, see Fig. 3, pre-formed or subsequently cut therein to register with the side outlet of pocket 12.

The confronting side faces of the slabs in registration with the pockets as indicated at 14 and 15, see Fig. 2, expose the slab embedded anchor members 16. Each is herein shown tubular or centrally cored and internally threaded as at 17. To prevent rotation wings 18 may be provided. To prevent axial withdrawing the rearward ends are enlarged as at 19. Herein same is of conical type.

15 When each anchor member is of fixed embedment type the foregoing suffices. When, however, slight play is desired each anchor member can bite into a conical sleeve of softer metal than the anchor, such as a lead sleeve, 20, see Fig. 5, and thus anchor rigidly in the slab when sufficient axial pull is exerted thereon, for the sleeve friction seats and locks the sleeve in the slab and the anchor locks to the sleeve.

An externally threaded connector 21 is seated 25 in each of the threaded sockets, and projects from the slab face exposing same. It is of a length less than the length of the socket. This member may be inserted following casting of the socket, and may serve as a means for attaching elevating 30 equipment when the slab is to be slipped into place in abutting relation to a previous slab and on a sand cushion 9, see Fig. 2.

When the slabs are aligned properly, the connector 21 is backed out of its supporting socket 35 and a sleeve coupling 22 is then threaded onto the aligned confronting members 21. Then when properly rotated, this connector 22 having tool engageable exterior 23 and right and left hand threads draws the two slabs together, or rather 40 the last laid slab to the previously connected slab and slabs, at the same time compressing the interposed sealing strips 11.

If the roadway, platform, landing run, etc. is of semi-permanent type the several pockets are 45 covered by caps 25 with inwardly flared side faces 26, see Fig. 4, which may be pitched or tarred to prevent leakage. When pressure fitted in the pocket the same is friction retained therein and with its top face flush with the slab load face. 50 When access to the pockets is desired the caps are "jimmied" therefrom. If the roadway, etc. is of permanent type, each pocket may be filled with a non-hardening asphalt mixture.

It is to be understood that only the preferred 55 form of anchoring and connector members is

herein illustrated but other forms as of reversed character though embodying at least one "turnbuckle" or reversed thread feature may be utilized.

Reference will now be had to Figs. 6 and 7. Herein 30 indicates a concrete curb, of precast type if desired. It includes an internally threaded sleeve 40 therethrough. A gutter apron slab 31, of precast type includes an embedded nut 32, same registering with sleeve 40. A bolt 41 is threaded through sleeve 40 and extends into the pocket 43 on the slab 31. Nut 42 on bolt 41 determines the pocket exposed length of bolt 41. Threaded member 44 is threaded home in nut 32 and projects into the pocket 43. A turnbuckle type coupling connector 45 serves to draw the gutter apron and curb slab together with seal 11 therebetween if utilized.

A catch basin 33 is provided at suitable intervals. It is closed by a grate 36 which may be of precast concrete or metal as desired. The catch basin above its bottom 33a includes in opposite sides outlets 34 which discharge to drain tiles 35 that lead to the drain sewer.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A concrete pavement comprising a plurality of precast slabs with pockets formed in certain side faces, opening upwardly and through said faces; anchor means exposed in each of said pockets; second anchor means carried by the slabs at faces removed from said pocket faces, said first and second anchor means of each slab being arranged whereby at opposing side faces

of adjacent slabs, a pocket anchor means of one slab is longitudinally aligned with one of said second anchor means; retractile connecting means interengaging said first and second anchor means across said pockets for drawing said slabs one toward the other and maintaining connection therebetween; each of said anchor means being embedded in the respective slabs and having an enlarged head remote from its exposed end; a compressible, complementary shaped sleeve enveloping each of said anchor means; said connecting means and anchor means having male and female thread connections therebetween; and means closing said pockets.

2. A concrete pavement comprising a plurality of precast slabs with pockets formed in certain side faces, opening upwardly and through said faces; anchor means exposed in each of said pockets; second anchor means carried by the slabs at faces removed from said pocket faces, said first and second anchor means of each slab being arranged whereby at opposing side faces of adjacent slabs, a pocket anchor means of one slab is longitudinally aligned with one of said second anchor means; retractile connecting means interengaging said first and second anchor means across said pockets for drawing said slabs one toward the other and maintaining connection therebetween; each of said anchor means being embedded in the respective slabs and having an enlarged head remote from its exposed end; a compressible, complementary shaped sleeve enveloping each of said anchor means; said connecting means and anchor means having male and female thread connections therebetween; and means closing said pockets.

3. A concrete pavement comprising a plurality of precast slabs with pockets formed in certain side faces, opening upwardly and through said faces; anchor means exposed in each of said pockets; second anchor means carried by the slabs at faces removed from said pocket faces, said first and second anchor means of each slab being arranged whereby at opposing side faces of adjacent slabs, a pocket anchor means of one slab is longitudinally aligned with one of said second anchor means; retractile connecting means interengaging said first and second anchor means across said pockets for drawing said slabs one toward the other and maintaining connection therebetween; each of said anchor means being embedded in the respective slabs and having an enlarged head remote from its exposed end; a compressible, complementary shaped sleeve enveloping each of said anchor means; said connecting means and anchor means having male and female thread connections therebetween; and means closing said pockets; said anchor means being internally threaded; and said connecting means comprising a pair of externally threaded members engaging respectively with the threads of opposing anchor means, and a reversely, internally threaded sleeve of a length less than that of said pockets and screw-threadedly engaging both of said threaded members.

FRANKLIN W. ABEL.
